(57) **CLAIM**

An ornamental design for an electronic device with portfolio risk view graphical user interface, as shown and described.

DESCRIPTION

FIG. 1 is a front view of a graphical user interface displayed on an unclaimed electronic device; and, FIG. 2 is a front view of a graphical user interface displayed on an unclaimed electronic device.

The broken lines represent the display screen, text, and portions of the graphical user interface and form no part of the claimed design.

1 Claim, 2 Drawing Sheets

FIG. 1

FIG. 2
